THERMAL SWITCH

Roland Dupont, Epernay, France

Application July 8, 1936, Serial No. 89,594
In France July 13, 1935

5 Claims. (Cl. 200—142)

In a patent application filed July 13, 1935, Serial No. 31,295, was described a "Press for electrically vulcanizing india-rubber pieces".

The present invention is an electric interrupter 5 destined to cooperate with the thermic hook arranged on the heating box.

The fusible metal is designed upon reaching the melting point to free the spring blade and break the electric current into the heating box, 10 various means being provided in order to release the spring blade by the use of the fusible material, in cooperation with a seesaw device.

In the drawings:

Fig. 1 shows a seesaw device held in normal 15 position by the fuse weight and closing the current circuit in the heating box.

Fig. 2 shows the same device positioned for breaking the current circuit upon melting of the fuse and rocking of the seesaw bar.

Fig. 3 is a view of the seesaw device with the 20 fuse enclosed into a spheric jacket.

Fig. 4 shows a similarly pivoted swinging bar with end hollows to receive the fuse.

Fig. 5 is a modification of Fig. 1.

25 The spring blade together with its hooking method described in the application No. 31,295 are substituted by a seesaw member 21 ensuring on the one hand the closure of the circuit for the heating resistances enclosed into the heating 30 box 16, under the action of the weight of a fusible mass 30, and on the other hand breaking the same circuit upon the reverse action of the same fusible mass, owing to its sliding, after being melted to the opposite end of the seesaw member.

35 According to the first embodiment, shown in Figs. 1 and 2, the fusible mass 30 has such a form as notwithstanding the existing slope between A and B (when contact between the electric contacts 19 and 20 is established) it cannot,

40 in the solid state, be removed from the point A. In case the fusible mass would be spheric, it is convenient to make a flat surface portion on which it may rest without rolling; if desired it is possible to make a small depression at the end 45 A of the bar 21 where the fuse is to be arranged.

According to this embodiment the fuse 30, having 50 reached its melting temperature by conductivity of the heat brought through the blade 31 directly subjected to the action of the inner resistances and also by the bar 21 in contact with this blade 31, flows along to B and swings the member 21 thus breaking the heating circuit at the points 20 and 20', Fig. 2. When the mass 30 is cold again in B, it is removed and put back at the point A for a following operation.

According to the embodiment of Fig. 3, the fusible mass 30 is enclosed in a light metal sphere, up to its half capacity or so and the sphere is then closed, the mass acting like a heavy weight in the solid state, the sphere will remain at the point A without revolving upon itself. Under the influence of the heat, the mass 30 is brought to the liquid state, and the sphere can run along from A to B, as in the previous case. When cold, the fusible mass is removed and arranged for another operation. In a third form of the device, Fig. 4, the arrangement is as follows: Each end A and B of the seesaw member 21 is made as a small box 21' with a half aperture opposite one to the other. The seesaw at the right time is rocked about its horizontal axis 19' and can also revolve about a vertical axis 19'' to bring the fusible mass in the box 21' around 180° to reset the device.

While this fusible mass is melting it flows along 20 to B and is received into the opposite box. The

fusible mass remains imprisoned in its housing and cannot escape out of same in any way unless in the liquid state. For this reason, the seesaw 25 bar can assume a horizontal rotary motion and the positions be reversed, the point A becoming B and reciprocally in view of successive operations without any other manipulation.

In the fourth embodiment of the invention according to Fig. 5, a simple ball or cylinder of 30 nonfusible metal of a sufficient weight is laid on the seesaw. This ball of inert metal is however keyed by a fusible metal piece 30' which, melting, releases the metal ball which then will run from A to B, thus causing the bar to go down 35 and break the current between 20 and 20'.

For each of the described devices and in order 40 that the two contacts 20 and 20' (between which is effected the rupture) are always in perfect contact, when the circuit is closed, the lower contact 20 is mounted on a tension spring 20'' sufficiently weak to be overcome by the weight of the fusible mass.

The small spring holding the contact 20 against the contact 20', when the seesaw is rocked, must 45 be limited in its movement in order that it cannot retain, when the seesaw is in breaking position, the contact 20 in contact with the contact 20'. From this reason, the contact 20 has in its lower part a shoulder 20''' which limits the movement 50 of same when moved upwards.

Furthermore the member 21 must be shaped, in each case, like a gutter so that the melted material cannot escape laterally while running from the point A to B.

Having now described the object of this invention and in which manner same is to be performed, what I claim is:

- 5 1. An electric switch comprising a support, a rocker member pivoted on said support on a horizontal axis, and having a longitudinal channel, a heat conducting blade on which one end of said rocker member may rest, a fusible body held on said one end of said rocker member to hold the same in an inclined position, and electrical contacts held closed by said rockable member when it is in contact with said blade, said fusible member, when fused by the heat conducted by said blade, being arranged to flow down the channel to the other end of said rocker member to overbalance it and thereby to open the circuit.
- 10 2. An electric switch comprising a support, a rocker member pivoted on said support on a horizontal axis, and having a longitudinal channel, a heat conducting blade on which one end of said rocker member may rest, a fusible body held on said one end of said rocker member to hold the same in an inclined position, and electrical contacts held closed by said rockable member when it is in contact with said blade, said fusible member, when fused by the heat conducted by said blade, being arranged to flow down the channel to the other end of said rocker member to overbalance it and thereby to open the circuit, said support being swivelly mounted to turn on a vertical axis.
- 15 3. An electric switch comprising a support, a rocker member pivoted on said support on a horizontal axis, and having a longitudinal channel, a heat conducting blade on which one end of said rocker member may rest, a fusible body held on said one end of said rocker member to hold the same in an inclined position, and electrical contacts held closed by said rockable member when it is in contact with said blade, said fusible member, when fused by the heat conducted by said blade, being arranged to flow down the channel to the other end of said rocker member to overbalance it and thereby to open the circuit,

said rockable member having pockets at its ends which communicate only with said channel and are adapted to contain the fusible member in its solid state.

4. In an electric switch, a supporting body, a 5 rocker member pivoted on said body on a horizontal axis, circuit contacts adapted to be controlled by said rocker member, said rocker member having a longitudinally disposed channel extending both ways from the pivotal axis, a heat 10 conducting blade carried by said supporting body, and having a rest portion for holding said rocker member in an inclined position with the higher end thereof in engagement with said rest portion, and a body including a fusible part for holding 15 said higher end in contact with said blade and thus to maintain the circuit contacts closed, said body being located in said channel and adapted when the fusible part melts to run down said channel to the lower end of said rocker member 20 to turn it on its pivot to separate the circuit contacts.

5. In an electric switch, a supporting body, a 25 rocker member pivoted on said body on a horizontal axis, circuit contacts adapted to be controlled by said rocker member, said rocker member having a longitudinally disposed channel extending both ways from the pivotal axis, a heat 30 conducting blade carried by said supporting body, and having a rest portion for holding said rocker member in an inclined position with the higher end thereof in engagement with said rest portion, and a body including a fusible part for holding 35 said higher end in contact with said blade and thus to maintain the circuit contacts closed, said body being located in said channel and adapted when the fusible part melts to run down said channel to the lower end of said rocker member to turn it on its pivot to separate the circuit contacts, said supporting body including a swivel 40 post to which said rocker member is pivoted, said post swiveling on a vertical axis.

ROLAND DUPONT.
